WINDOW MASKING DEVICE FOR RUBBER MOUNTED WINDOWS

Morris Mund, Philadelphia, Pa.

Application June 12, 1957, Serial No. 665,248

6 Claims. (Cl. 118—505)

This invention relates to a masking device for a rubber mounted window while spray painting the area about and adjacent said window. As is well known, rubber mounted window structures are used in air conditioned trains, buses, and like structures.

Heretofore in coating or painting, especially spray painting, surfaces adjacent to and about such windows it has been necessary to use masking tape to cover the windows or portions thereof, especially at the edges thereof, with masking tape to protect them from being painted during the spraying operation. Also, multi-piece masking devices and masking devices comprising complicated fastening means have been used. However, it has been found that the masking means and devices presently utilized and heretofore applied have not provided a practical nor economical means for arriving at the solution of the problem presently existing in this art. The use of the heretofore known devices and means for masking the rubber mounted windows during the spraying operation is costly and requires much time, effort and material.

Various types of masking devices for rubber mounted windows have been introduced by prior workers in the art for doing away with masking tapes or papers or other selective covering means, and in each of these cases, serious problems such as waste of costly time and material have presented themselves. Also, the prior art devices have not provided effectively the desired degree of covering to insure a clean, desirable and workmanlike job.

With the masking device of this invention, I have obviated and have permanently eliminated the problems set forth, including loss of valuable time by high salaried personnel employed in this field and waste of costly material. The masking device of my invention is capable of being installed to cover the window within a few seconds and, in addition, provides an effective degree of covering to insure a clear, desirable, and workmanlike job at the completion of the work.

The masking device of my invention comprises a sheet of material having a shape or configuration of the shape of the rubber mounted window to be masked, means operatively associated with said sheet for engaging the rubber mounting of the window, said engaging means comprising a plurality of plate members which are spaced from and parallel to said sheet, each of said plate members being individually associated with said sheet, means for moving said plate members into engagement with the rubber mounting, preferably at spaced apart points of said rubber mounting, and means for fixedly positioning said plate members in engagement with the rubber mounting, said fixedly positioning means being operatively associated with said moving means.

An object of my invention is to provide a window masking device for rubber mounted windows capable of absolutely minimizing the time required for masking the window which is not to be painted during a spray painting operation, thereby reducing the labor cost for masking the window and effecting a great saving in job cost.

2

Another object of my invention is to provide a window masking device for rubber mounted windows to eliminate the waste of masking tapes which can be used only once.

Another object of my invention is to provide a window masking device for rubber mounted windows which can be used over and over again.

Other objects and features of my invention will become apparent from the following detailed description which is not intended to be limiting but is set forth here 10 as a preferred embodiment.

Figure 1 is a view in perspective of the masking device mounted over a rubber mounted window.

Figure 2 is a view in perspective of the sheet of material of the masking device shown in Figure 1.

Figure 3 is a view in perspective of a sheet of material similar to that shown in Figures 1 and 2 but for a window larger than that shown in Figure 1.

Figure 4 is a section taken on line 4—4 of Figure 1 in the direction of the arrows.

Figure 5 is an exploded view of the portion of the device as seen in Figure 1.

Like numerals designate similar component parts.

More specifically, there is provided a sheet of material 10 preferably having a flange 12 therearound. The sheet 10 has the shape or configuration of the window 14 which is to be covered thereby and said sheet may be of any shape depending upon the shape of the window to be covered thereby. The window 14 is a rubber mounted window, as is clearly evident from Figure 4. As is well known in the art, a rubber mounting is positioned in a groove, and the window is fixed therein, as is shown in Figure 4. The rubber mounting 16 comprises a curved portion 18 having flange members 20, 20 integral therewith and extending therefrom. Sheet 10 has therethrough the substantially longitudinal slots 22, 22 which are adjacent to edge portions, preferably opposite edge portions, of said sheet from which said flange 12 depends. The dimensions of the sheet 10 are such that the sheet 10 extends over the top surface 24 of flange 20, as is clearly shown in Figure 4. A stud member 26, preferably threaded, extends through each slot 22, and the stud member 26 is movable in and along each slot 22. Attached to the end of said stud member 26 is plate member 28, for example, as by brazing, in such a manner that plate member 28 is substantially parallel to the sheet 10. Positioned about stud member 26 is a spacer member 30 of such dimensions that it is retained between plate member 28 and the surface 32 of sheet 10 and that its height is preferably less than the height of flange member 20 of the rubber mounting 16. Positioned about stud member 26 is washer member 34 between surface 36 of sheet 10 and the end 38 of stud member 26. Washer member 34 is of such dimensions that it at all times entirely covers slot 22. Threadedly engaging stud member 26 at the portion thereof extending above washer member 34 is the tightening means here shown as a wing nut 40. The plate member 28 may be any regular shape such as hexagonal, as here shown in Figure 5. The sheet 10 may be of such dimensions that it will extend over the top surface 24 of the flange 20 of the rubber mounting 16 or at least to the edge 42 of said top surface 24. For a larger window a sheet 44 having therethrough the slots 46 positioned as shown in Figure 3 may be used in place of sheet 10, the window to be covered thereby having the same configuration as shown in Figure 3. Sheet 44 may also have a flange 48 therearound.

In using the masking device 50 as shown in the appended drawings, the device 50 is so positioned that the sheet 10 covers the window 14 and the flange 12 is positioned between the rubber flange 20 and the edge of the area S to be painted, as clearly shown in Figure 4. Each

stud member 26 is moved in and along its slot 22 in a direction towards the rubber flange 20 until the edge of the plate 28 engages rubber flange 20. The wing nut 40 is then tightened against the washer 34. Thereby is the masking device 50 including the sheet 10 fixedly positioned to cover the window. The same procedure is followed in utilizing the masking device without the flange 12. In this case, the bottom surface 32 of sheet 10 is so positioned that its edge engages the edge 42 of the top surface 24 of the rubber flange 20 or that the outer portions thereof adjacent its edge overlaps the top surface 24 of the rubber flange 20.

It is obvious that my masking device may be used to cover rubber mounted windows of different sizes by merely changing the sheet of material to conform with the shape of the window to be masked.

It may also be clearly seen here that construction comprising the threaded stud member and the wing nut is a preferred embodiment and that other similar structures may be utilized.

The sheet material members 10 and 44, as hereinabove set forth, are of stiff, flexible, and resilient material, such as plastic sheets, aluminum sheets, copper sheets, brass sheets, and the like.

Many changes and alterations may be made without departing from the spirit and scope of this invention which is set forth in the appended claims which are to be construed as broadly as possible in view of the prior art.

I claim:

1. A masking device for covering a rubber mounted window while spray painting the area about and adjacent said window, comprising, in combination, a sheet of material having the configuration of said window, said material being parallel with said window, means for engaging the rubber mounting of the window, said means including a plurality of elongated openings in said sheet of material and a plurality of rubber mounting engaging members extending through said elongated openings and moveable parallel to said window and said sheet of material, means for moving said rubber mounting engaging members into engagement with the rubber mounting of the window, and means for fixedly positioning said rubber mounting engaging members in engagement with said rubber mounting, said fixedly positioning means being operatively associated with said moving means, whereby the window is masked thereby preventing the paint from reaching it.

2. A masking device for covering a rubber mounted window while spray painting the area about and adjacent said window, comprising, in combination, a sheet of material having the configuration of said window, said material being parallel with said window, said sheet having a flange substantially perpendicular thereto at its edge, means for engaging the rubber mounting of the window, said means including a plurality of elongated openings in said sheet of material near the edges thereof and a plurality of rubber mounting engaging members extending through said elongated openings and moveable parallel to said window and said sheet of material, means for moving said rubber mounting engaging members into engagement with the rubber mounting of the window, and means for fixedly positioning said rubber mounting engaging members in engagement with said rubber mounting, said fixedly positioning means being operatively associated with said moving means, whereby said sheet of material may be positioned over said window in such a manner that the flange is positioned between the rubber mounting and the edge of the area to be painted and whereby the rubber mounting engaging members may be caused to engage the rubber mounting and to be fixedly positioned thereagainst, thereby masking the window to prevent paint from reaching it.

3. A masking device for covering a rubber mounted window while spray painting the area about and adjacent said window, comprising, in combination, a sheet of ma-

terial having the configuration of said window, said sheet having one surface adapted to face the window, said sheet having at least two substantially elongated slots therethrough, said slots being positioned in portions of said sheet adjacent to opposite edge portions of said sheet, a stud member extending through each slot, each stud member being threaded at at least one end portion thereof, each stud member being movable in and along each slot, each stud member having a plate member attached to the other end portion thereof and substantially parallel to the sheet of material, a spacer member positioned about the portion of the stud member between the sheet surface adapted to face the window and a plate member surface, a washer member positioned about each stud member between the other sheet surface and the end of the threaded end portion thereof, and means for tightening each washer against said other sheet surface, said means threadedly engaging said threaded end portion of each stud, whereby said sheet of material may be placed over said window in such a manner that the plate members are positioned between said window and the sheet surface facing said window, whereby each of the stud members may be moved in and along its respective slot towards the rubber window mounting thereby causing the respective plate members to engage said rubber window mounting, and whereby each of said washers may be tightened against said other surface after said plate members have been caused to engage said rubber window mounting, thereby to fixedly position said sheet of material to cover the window.

4. A masking device for covering a rubber mounted window while spray painting the area about and adjacent said window, comprising in combination a sheet of material having the configuration of said window, said sheet having one surface adapted to face the window, said sheet having a flange substantially perpendicular thereto and integral therewith at all points of its edge, said sheet having at least two substantially elongated slots therethrough, said slots being positioned in portions of said sheet adjacent to opposite edge portions of said sheet, a stud member extending through each slot, each stud member being threaded at at least one end portion thereof, each stud member being movable in and along each slot, each stud member having a plate member attached to the other end portion thereof and substantially parallel to the sheet of material, a spacer member positioned about the portion of the stud member between the sheet surface adapted to face the window and a plate member surface, a washer member positioned about each stud member between the other sheet surface and the end of the threaded end portion thereof, and means for tightening each washer against said other sheet surface, said means threadedly engaging said threaded end portion of each stud, whereby said sheet of material may be placed over said window in such a manner that the plate members are positioned between said window and the sheet surface facing said window and the flange of said sheet of material is positioned between the rubber window mounting and the edge of the area to be painted, whereby each of the stud members may be moved in and along its respective slot towards the rubber window mounting thereby causing the respective plate members to engage said rubber window mounting, and whereby each of said washers may be tightened against said other surface after said plate members have been caused to engage said rubber window mounting, thereby to fixedly position said sheet of material to cover the window.

5. A masking device for covering a rubber mounted window while spray painting the area about and adjacent said window, comprising, in combination, a single unitary sheet of stiff, flexible, and resilient material having the configuration of said entire window, said material being parallel with said window, means for engaging the rubber mounting of the window, said means including a plurality of elongated openings in said sheet of material and a plu-

rality of rubber mounting engaging members extending through said elongated openings and movable parallel to said window and said sheet of material, means for moving said rubber mounting engaging members into engagement with the rubber mounting of the window, and means for fixedly positioning said rubber mounting engaging members in engagement with said rubber mounting, said fixedly positioning means being operatively associated with said moving means, whereby the window is masked thereby preventing the paint from reaching it.

6. A masking device for covering a rubber mounted window while spray painting the area about and adjacent said window, comprising, in combination, a sheet of material having the configuration of said window and extending over at least a portion of said rubber mounting, means for frictionally engaging the rubber mounting of the window, said means including a plurality of elongated openings in said sheet of material and a plurality of rub-

ber mounting engaging members extending through said elongated openings and movable parallel to said window and said sheet of material, means for moving said rubber mounting engaging members into engagement with the rubber mounting of the window, and means for fixedly positioning said rubber mounting engaging members in frictional engagement with said rubber mounting, said fixedly positioning means being operatively associated with said moving means, whereby the window is masked thereby preventing the paint from reaching it.
